[57] ABSTRACT

An apparatus for developing an electrostatic latent image which includes a housing rotatable about an axis for conveying developer to the image. The housing includes a sloped inner surface which increases in distance from the axis in an upward direction and includes a top surface which lies in a plane substantially perpendicular to the axis to confront an electrostatic image to develop. Rotation of the housing centrifugally impels developer from the bottom of the housing along the inner sloped surface to the top surface of the housing in order to develop the image.

CENTRIFUGAL DEVELOPMENT APPARATUS AND METHOD

BACKGROUND OF THE INVENTION

This invention relates in general to developing latent electrostatic images and, in particular, relates to an apparatus for centrifugally bringing developer material into contact with a photosensitive surface in order to develop a latent electrostatic image thereon.

More specifically this invention relates to a development device wherein developer is lifted from a sump by centrifugal force to a latent electrostatic image to be developed to convey developer in multiple directions past the surface on which the image is positioned. The developer is conveyed to the image by being centrifugally impelled against the sloped inner surface of a rotating housing to move thereon.

In the process of xerography, the xerographic plate comprising a layer of photoconductive material on a conductive backing is given an uniform electric charge on its surface and then is exposed to the subject matter to be reproduced by various projection techniques. This exposure discharges the plate in accordance with the light intensity reaching it thereby creating a latent electrostatic image on or in the plate. Development of the image is effected by developers which may comprise, in general, a mixture of suitable, pigmented or dyed, resin base powder, hereinafter referred to as toner, which is brought into contact with the plate by various well-known development techniques. During such development of the image, the toner powder is brought into surface contact with the photoconductive coating and is held there electrostatically in a pattern corresponding to the latent electrostatic image. Thereafter, the developed xerographic image may be transferred to a support material to which it may be fixed by any suitable means such as heat fusing.

Various development devices have been utilized in xerography to develop an electrostatic image formed on a photoconductive surface. One well-known technique of development is disclosed in the U.S. Pat. No. 2,573,881 to Walkup et al. wherein toner carried by carrier particles is rolled or cascaded over the electrostatic image bearing surface. The carrier and toner materials are selected so that a triboelectric attraction exists between them causing the two particles to cling together and acquire an opposite charge. Each carrier has numerous toner particles attracted thereon allowing them to be transported into contact with the photoconductive surface where the greater electrostatic attraction of the latent image will overcome the triboelectric attraction between the two developer components causing toner to be stripped off the carrier and electrostatically bonded to the charged image to effect development.

Another suitable manner of developing a latent electrostatic image is by creating a cloud of toner which comes into contact with the photoconductive surface. This mode of developing is disclosed in U.S. Pat. No. 2,928,575 to Carlson wherein a powder cloud is created in a generator by air pressure and an electrostatic charge is placed on the toner by contact of the cloud with the wall of the generator. The charged particles in cloud form thereupon are moved in the vicinity of the latent electrostatic image for development thereof. Therefore, in powder cloud development the charged toner comes into contact with the image without being affixed to a carrier at the time of development. Besides cascade and powder cloud techniques many other modes of development are utilized in the art. Among these are: magnetic brush development as disclosed in U.S. Pat. No. 3,176,652 to Mott et al.; doner development as disclosed in U.S. Pat. No. 3,216,844 to King; fur brush development as disclosed in U.S. Pat. No. 3,251,706 to Walkup and the like.

Several difficulties are associated with the previous methods of development. Cascade development, for example, presents a problem in developing large area images. Generally, the electric field of an electrostatic image is stronger at the edges than in the central portion. Therefore, the lines of force at the

edges are sufficient to attract toner from the carrier, but in the central portion the toner is not attracted to the image since the field is not strong enough to overcome the triboelectric attraction of the two components of the developer. Such a phenomena will result in incomplete development in the central portions of an image while the edges normally are sufficiently developed.

10 Cascade development also requires a thorough intermixing of the developer after repeated development of an image. If inter-mixing does not occur, a defect in development appearing an image striations will result, because of localized carrier material becoming depleted of toner powder. Since images normally have varying size latent image areas to be developed along the direction of flow, repeated development causes the developer flow moving past the more massive image areas to be depleted of toner in a greater amount than the less massive image areas causing certain areas of the developer flow to be depleted of toner more than others. Elaborate systems for 15 inter-mixing of developers, therefore, are required to overcome this toner depletion difficulty.

The aforementioned powder cloud development technique does overcome large area development problems as presented by cascade development since toner is presented to the electrostatic image without being accompanied by carrier particles. Therefore, the electrostatic attraction of the latent image does not have to compete with the triboelectric attraction between toner and carrier which allows the toner to more readily affix to the weaker attraction of the central portion. However, powder cloud development suffers from other drawbacks including a tendency to develop the non-image "background" areas of the photoconductive surface. A photoconductive surface contains residual charge in areas other than the image area and the toner in a powder cloud unaccompanied by carrier particles will develop the so-called "background" area because the residual electrostatic field remaining after exposure of the photoreceptor does not have to compete with the triboelectric attraction between the development particles as in a cascade system. Further, the generation of high velocity toner cloud flow conditions in prior art powder cloud devices causes directional development defects which appear as streaks in the developed image, since the toner passes the photoconductive surface in only one direction.

Therefore, it becomes desirable in xerography to provide an improved development apparatus which overcomes many of the aforementioned problems presented by the prior art development means. For example, such an improved device 50 should adequately develop solid image areas with a minimum of toner starvation of the carrier particles as usually produced by the cascade technique of development. Further, it is advantageous that an improved development device be provided which does not produce directional effects such as streaking 55 of an image.

SUMMARY OF THE INVENTION

It is, therefore, an object of this invention to develop a latent electrostatic image with an improved apparatus.

Another object of this invention is to improve the development of the solid areas of a latent electrostatic image.

A further object of this invention is to eliminate elaborate developer conveying and inter-mixing systems in a development apparatus.

Still another object of this invention is to present developer to the latent electrostatic image area in multiple directions.

A still further object of this invention is to improve a development apparatus by presenting developer to a latent

0 electrostatic image area in a more uniform flow pattern.

Another object of this invention is to better develop a latent electrostatic image with a magnetic field inducing device in a development apparatus.

These and other objects are obtained in accordance with
5 the present invention wherein there is provided an effective

and inexpensive development device which overcomes many of the aforementioned difficulties presented by the cascade, powder cloud, and other development systems. The invention comprises a non-complicated system having but one moving part and a self-circulating developer feature. The novel development devices disclosed herein will efficiently overcome solid area development problems of the cascade method as well as minimize the formation of image striations. The latter problem is solved because developer is conveyed past the image area on the photoreceptor in multiple directions and toner depletion in specific areas of developer flow is thereby kept to a minimum. Therefore, elaborate developer inter-mixing means necessary in the cascade technique of development is not required by the present invention. Further, many of the problems presented by use of the powder cloud technique are alleviated by the development devices of the invention because a two component developer as well as development electrode means is utilized in the present invention to aid in overcoming such difficulties as undesired development of non-image areas inherent in powder cloud devices.

The novel devices described herein accomplish these results by centrifugally conveying developer material to a surface bearing a latent electrostatic image to be developed. A rotating housing is the essential moving part of the invention and included in the devices disclosed herein is a self-circulating developer feature. Also, the present invention overcomes solid area and background difficulties by utilizing a surface of the centrifugal developer conveying means as a development electrode to increase the lines of electrostatic force of the central portion of the image area. Further, the high flow velocities inherent in the instant centrifugal development apparatus has been found to prevent sticking or "beading" of carrier beads to the charged image or other areas of the photoconductive surface as occasioned in the use of other two component developer systems such as in cascade devices.

DESCRIPTION OF THE DRAWING

Further objects of this invention together with additional features contributing thereto and advantages accruing therefrom will be apparent from the following description of several embodiments of the invention when read in conjunction with the accompanying drawings wherein:

FIG. 1 is a schematic illustration of a belt type xerographic machine utilizing the development device of the present invention;

FIG. 2 is a perspective illustration of one embodiment of the development device according to the present invention;

FIG. 3 is a schematic illustration of the embodiment of the invention illustrated in FIG. 2;

FIG. 4 is a schematic illustration of a second embodiment of the development device according to the present invention;

FIG. 5 is a schematic illustration of another embodiment of the development device according to the present invention;

FIG. 6 is a schematic illustration of another embodiment of the development device according to the present invention; and

FIG. 7 is a perspective illustration of the flow of developer past a surface bearing a latent electrostatic image according to the present invention.

DESCRIPTION OF THE PREFERRED EMBODIMENTS

Referring to FIG. 1, there is shown a schematic view of a belt type xerographic machine utilizing the development devices of the present invention. The essential element of the machine is a belt 1 mounted on suitable rollers and drivable in a conventional direction by a motor (not shown). The belt 1 comprises an outer surface with a layer on photoconductive insulating material such as vitreous selenium or other suitable surface. An uniform electrostatic charge is placed on the photoconductive surface of the belt 1 by means of a conventional corona charging device 2. The uniformly charged sur-

face on the belt is then moved to exposure means 3, which may be any well-known device which will expose the charged surface to copy to be reproduced and form a latent electrostatic image of the copy on the photosensitive belt surface.

Following the formation of a latent electrostatic image of the copy, the image on the belt will move to the development device 10 according to the present invention (to be described in detail later) to bring the latent image into contact with developer material for development thereof. After development, the visible image moves to a transfer means 4 and is transferred from the belt to a web of paper 5 or the like which is positioned in contact with the belt by rollers 6. A second corona charge device 7 applies a charge to the back of the web 5 to facilitate transfer of the toner powder in image form. The toner image on the web then moves past a heating element 8 which permanently affixes the toner to the paper web to form a duplicate of the original copy. A rotating brush 9 contacts the belt surface after it moves past the transfer device 4 to remove any residual image material on the surface prior to a subsequent reproduction cycle. It is clear that other modes of charging, exposing, transfer, or fusing may be utilized in connection with the present invention.

Referring now to FIGS. 2 and 3, there is illustrated a first embodiment of the development device 10 shown in FIG. 1 according to the present invention. In particular in FIGS. 2 and 3, there is shown a rotating housing 11 journaled on a vertical shaft 12 surrounded by sleeve 13 which is connected to a base plate 14 by use of threads. Sealed ball bearings 16 are located at both ends of the sleeve 13 to surround the shaft 12 to allow rotation of the shaft relative to the sleeve. The shaft 12 is journaled at one end by bearings 16 and is connected to a flexible drive belt 17 adjacent thereto. The flexible belt 17 is connected to a conventional variable speed motor M that is mounted on brackets (not shown) beneath the base plate 14 which effects rotation of the shaft.

A cover member 18 is affixed to the upper end of the shaft by suitable means to substantially close the upper portion of the housing 11 wherein an opening 18a is provided between the periphery of the cover and the top of the housing to allow developer flow therebetween. A vane support member 18b is surroundingly affixed by suitable means to a hub portion of the cover member to receive and retain a series of vane members 19. The vane members are shown in FIGS. 2 and 3 for convenience of illustration as two flat vertically oriented vanes although the vane members may comprise other numbers and other oriented shapes, as for example, helical forms and the like. The vane member 19 extends radially from the vane support member 18 to the inner surface 20 of the wall 21 of the housing 11 and is fixed thereto in slots 22. The vanes extend vertically along the entire height of the inner surface of the housing and include at the bottom thereof scoops 23 in the form of plows which extend below the bottom of wall means 21 and are curved into the direction of rotation of the housing.

The inner surface 20 is in a conical shape extending the height of the housing wall. For example, the inner wall 20 may be sloped at a 60° angle with respect to horizontal, but it should be apparent that other slopes may be utilized according to the present invention depending on desired developer flow. The wall further includes a horizontal top surface 24 and a vertical outer surface 25 adjacent the top surface. The vertical outer surface 25 extends partially downward to meet a horizontal under surface 26 and the rest of the outer surface of the wall then comprises a sloped outer surface 27. The sloped outer surface 27 is illustrated as being sloped at a different angle with respect to the horizontal than is the inner surface wall 20, but may encompass any other desired slopes or shapes. In the construction thus far described, it should be apparent that the housing wall 21, the vanes 19, and the vane support member 18, and the shaft 12 all rotate unitarily about the axis of rotation of the shaft and are rotated by motor M.

An annular conductive disc member 30 which can be made of any suitable conductive material is unitarily mounted on the top surface of the housing and is of a height to allow flow

through the opening 18a. The inner surface 31 of the annular disc is sloped correspondingly to the inner conical surface to be a mere extension thereof. The top surface 32 of the annular disc is sloped outwardly at a slight angle with respect to the horizontal. For example, one construction of the novel device disclosed herein extended a width of two inches from the inner edge to the outer edge of the top surface of the annular disc. The outer edge of the disc in such a form was elevated 30/1,000 of an inch from the elevation of the inner edge of the surface.

The annular disc is electrically grounded through the wall of the housing, vanes, vane support member and shaft thereby acting as a development electrode to increase the lines of force emanating from the latent electrostatic image. The annular disc, the housing wall 21, vanes 19, vane support member 18 and shaft 12 are formed of a suitable conductive material such as a metal to allow the disc to be grounded through the body of the device. However, the materials used in construction of these latter mentioned elements is not intended to be limited to a conductive material, and it is within the scope of this invention to use suitable non-conductive materials for one or more of these elements. In such a case the annular disc 30 may be grounded directly in a conventional manner (not shown). Also, the annular disc may be biased by an electrical potential (not shown) to further modify the electrical field of the latent image to better develop a solid image area or to control the deposit of toner in the background non-image areas of the surface.

The belt 1 having an outer layer of photoconductive material with an electrostatic image to be developed thereupon is spaced a small distance from the annular top surface 32. The latent image confronts the top annular surface along a substantially horizontal plane and moves relative to the housing 11. The novel developer device of the present invention includes a developer catching wall 33 which will receive developer flow (to be described later) as it comes off the top annular surface and guides unused developer by gravity to the base plate 14. The base plate 14 acts as a support or sump for the developer material to be circulated and the developer supported thereby is preferably a two component developer comprising carrier and toner such as, for example, disclosed in the U.S. Pat. No. 2,618,551 to Walkup. A sufficient amount of developer is retained by the base plate to insure uniform and adequate circulation of the carrier and toner particles.

In operation of the embodiment in FIG. 2, the shaft, vane support member, vane wall, and the annular member rotate together as a one piece housing driven by the motor M. The developer which is supported on the base plate 14 is picked up by scoops 23 on the vanes 19 upon rotation of the housing. The scoops are shaped so that their movement will pick up developer and place it in contact with the sloped inner surface 20. The rotation of housing causes the developer in contact to be hurled upon the inner surface by centrifugal force. Since the inner surface is sloped, a vertical force component is applied to the particles by the rotation which results in the particles moving up the wall to the annular top surface 32. The annular top surface is nearly horizontally oriented and, therefore, the developer is hurled in all directions across the annular surface in the space between it and the photoreceptor surface. The uniformity of the developer flow across the annular disc is increased by the cover member 18 which insures that flow only is directed through the opening 18a between the cover and the annular disc. As illustrated in FIG. 7, the flow across the annular disc is not perfectly radial because the rotation of the housing normally causes the developer to leave the annular surface at an angle to the radial direction.

Since the space between the annular disc and the charged image is small, flow of developer between the two elements causes toner to be in contact with the latent image to thereby affix toner thereto. The top annular surface is sloped slightly in the direction of flow, as previously discussed, to maintain or increase the interference of the developer material with the photoconductive surface as well as to control developer flow.

It is advantageous to slope the upper annular surface because the flow area increases as the circumference of the disc becomes greater in an outward direction and, therefore, the slope surface will act to maintain developer flow density approximately constant. The developer will contact the charged image from multiple directions as most clearly illustrated in FIG. 6, because of the substantial radial flow across the annular surface and the movement of the belt relative thereto. As a result, the problem of toner depletion of the carrier particles as experienced in the cascade process is reduced to a minimum since specific parts of the image are not exposed only to one specific area of developer flow.

The unused developer is caught by catching wall 33 surrounding the annular surface and by gravity returns to base plate 14 to be recirculated. Therefore, the development apparatus of the invention includes a self-circulating feature to return unused developer to the sump for subsequent use which alleviates expensive circulating means of prior art development devices. Further, it is within the scope of the present invention to use any desired slope angle of the inner surface or rotational speed of the housing which affords suitable development results depending on presented conditions. Furthermore, the inner surface need not be limited to one uniform slope and can comprise a surface having two or more slope angles or other shaped surfaces such as, for example, an elliptical profile.

Referring now in particular to FIG. 4, there is illustrated another embodiment of the development device according to this invention. This embodiment is identical to the embodiment shown in FIGS. 2 and 3, except it further includes developer agitation or turbulence inducing means comprising a roughened upper surface 40 of the annular disc 30. In FIG. 4, the roughened surface 40 is shown in the form of serrations which tend to agitate the developer into better development contact with the electrostatic image. Also, as an alternative or additional aid for development using the device of FIG. 4, a magnetic field is set up about the annular disc by magnets 41 as shown in FIG. 4. The magnets 41 are stationary segments mounted by suitable means (not shown) beneath the annular disc 30 which allows relative motion between the electrode disc 30 and the magnet, whereby a magnetic field is alternately applied to specific areas of the rotating surface. The resulting magnetic field alternately applied utilizing the segmented magnets will increase turbulence of the developer passing the latent image as well as create a compacting of the developer in contact with the image area producing more interference of toner and carrier with the image bearing surface to effect better development of the latent image lying thereon. Using the magnetic field as a development aid in this embodiment would require the use of a developer material which comprises well-known ferro-metallic carrier particles that are readily deflected by the field. Also, when employing the magnetic field in this embodiment as a development aid, it is desirable to use a disc 30 made of a suitable material which minimizes Eddy current losses such as, for example, a well known semi-conductive material.

Referring now to FIG. 5, another embodiment of the development device according to the present invention is illustrated. This embodiment is identical to the embodiment in FIGS. 2 and 3 except it includes an alternative means for inducing a magnetic field about the annular disc surface. The magnetic field in this embodiment is produced by annular disc magnet 42 mounted by suitable means (not shown) to the bottom surface of the disc 30 to rotate therewith. The annular disc magnet 42 creates an annular magnetic field about the axis of rotation of the housing which retards the movement of the developer flow being guided across the annular surface. The force field created by the annular magnet thereby produces a barrier to impede and slow developer flow reaching the field which consequently results in developer material flow not yet reaching the barrier to also slow in velocity. The amount of this decrease of the developer material velocity across the disc surface depends on the strength of

the magnetic field created by the magnet and therefore by selecting a desired field intensity a particular velocity pattern may be selected for flow across the annular disc surface. Thus the developer flow in this embodiment is controlled to a desired flow velocity without the need of a physical structure to block the flow which may disrupt the uniform flow pattern across the annular disc. Therefore, since the flow on the disc is impeded, a backup of developer flow occurs on the disc surface to effect brush-like contact of the developer thereon against the belt 1 bearing an image to be developed and thus specific areas of developer material are in contact with the photoconductive surface for a greater length of time to produce effective development. The developer material flowing directly in the magnetic field and impeded therein is thereafter hurled into contact with the catching wall 33 to be returned to the sump as in the aforementioned embodiments of the invention. The annular disc and developer material of this embodiment may, for example, respectively comprise the material previously disclosed in the embodiment of FIG. 4.

In reference to FIG. 6, there illustrated still another embodiment of the development device according to this invention. In particular in FIG. 6, the principal of operation is identical to the embodiment illustrated in FIGS. 2 and 3. However, instead of utilizing a sloped inner surface of the housing, the embodiment of FIG. 6 utilizes a plurality of slanted thin wall tubes 50 to convey the developer to the latent image area. The tubes are supported near the lower end by support rings 51 connected to rotating shaft 52. The tubes are of any suitable non-metallic or metallic material such as, for example, brass and are retained at their upper end by holes 53 in a thin disc-like plate 54. The upper open ends 55 of the tubes are flush with the upper surface of the disc 54 to form a smooth upper surface. The disc is fixedly supported by suitable means (not shown), on the rotating shaft and a hub-like support member 55 surrounds the shaft and extends from the top of the support rings 51 to the bottom of the disc 54 to give better physical support to the structure.

The shaft 52 is journaled at its bottom in a similar fashion as described for the embodiment of FIG. 2 so as to be rotated by a variable speed motor M. Rotation of the shaft in FIG. 5 will cause the support ring 51, the hub support member 55, the slanted tubes 50 and the disc 54 to rotate as a unitary unit about the axis of the shaft 52. The top of the disc is gradually elevated in an outward direction similarly to the top annular surface of the embodiment shown in FIGS. 2 and 3 to keep the developer in development contact with the latent image lying on a surface downwardly confronting the top disc surface.

The slanted tubes 50 have a slanted opening 56 at the bottom of the tube which extends into the developer material supported by the base plate 14. The slanted opening faces the direction of rotation of the shaft and thereby scoops up developer comprising carrier and toner particles into the entrance of the tube. By centrifugal force the scooped developer is impelled against the sides of the tubes and because of their slanted orientation, the developer moves up the tube to the opening on the disc member. The developer is then hurled outwardly with a radial component of velocity in a manner similar to that illustrated in FIG. 7 for the other described embodiments.

The developer catching means 33 and base plate of this embodiment are identical as described in conjunction with FIGS. 2 and 3. Therefore, the thin wall tubes function to convey developer in a manner similar to the conical surface previously described. Further, the annular disc of this embodiment can function as a development electrode, since it also may be grounded through the body of the development device or be directly grounded. If a greater electric field was required in the area of the image, the annular disc of this form of the invention could also be connected to an electrical bias potential to give greater or improved solid area development or a suitable bias may be applied to reduce the deposit of toner in background areas on the photoconductor.

In the above description that has been disclosed improved devices for effectively developing a latent electrostatic image supported on a xerographic photosensitive surface. The surface to be developed was described for convenience of illustration as being that of a xerographic belt, but may be used to develop other well-known photoconductive members in the form of plates, drums, webs or coated papers.

While the invention has been described with reference to preferred embodiments, it will be understood by those skilled in the art that various changes may be made and equivalents may be substituted for elements thereof without departing from the true spirit and scope of the invention. In addition, many modifications may be made to adapt a particular situation or material to the teachings of the invention without departing from its essential teachings.

What is claimed is:

- Latent image developing apparatus comprising a support surface bearing a latent electrostatic image to be developed, developer material for developing said latent image when positioned adjacent to the latent image, a housing journaled for rotation about an axis generally perpendicular to the support surface including means for containing said developer material for radially accelerating the material by rotating the housing and exit means for allowing accelerated developer material to travel radially outward relative to the housing in a plane generally parallel to said support surface whereby the radially accelerated developer material makes multiple directional contact with the support surface for developing the latent image.
- The apparatus of claim 1 wherein the housing is adapted to be positioned adjacent a relatively movable image bearing surface to be developed.
- The apparatus of claim 1 wherein the developer material comprises a two component developer including carrier particles and toner powder to develop the latent image.
- The apparatus of claim 1 further including guide means spaced from the support surface and generally parallel thereto for guiding radially propelled developer material over the support surface.
- The apparatus of claim 4 wherein said guide means is electrically conductive and further including an electrical bias coupled to the guide means for development of the latent image.
- The apparatus of claim 4 wherein said guide means comprises an annular surface in close spaced confrontation with the image bearing surface.
- The apparatus of claim 6 wherein developer material flow is guided outwardly on the entire annular surface to contact the image bearing surface.
- The apparatus of claim 6 wherein said annular surface is radially inclined at a small angle to progressively decrease the space of confrontation between the image bearing surface and the annular surface in a radial direction from the axis.
- The apparatus of claim 6 wherein the guide means is an electrically grounded conductive member to form a development electrode.
- The apparatus of claim 4 wherein the guide means includes a roughened surface to agitate developer material into contact with the image bearing surface.
- The apparatus of claim 4 wherein the guide means includes a magnetic field means to agitate the developer material into contact with the image bearing surface.
- The apparatus of claim 4 wherein the housing further includes a developer receiving means mounted adjacent the guide means to receive developer material after contacting the image bearing surface to return unused developer material to the sump.
- The apparatus of claim 1 wherein said housing containing means includes inner wall surfaces sloped relative to the axis of rotation to cause developer material to flow along the wall when the housing is rotated and said housing further in-

cluding a sump for storing developer material adjacent said inner walls such that developer material moves from the sump along the inner walls when the housing is rotated.

14. The apparatus of claim 13 wherein the inner surfaces comprise a plurality of sloped tubular members.

15. An apparatus for developing a support surface bearing a latent electrostatic image with developer material comprising conveying means to effect a flow of developer material past an image bearing surface for development contact therewith including a disc surface carrying the developer flow in multiple directions past the image bearing surface and

force field means operatively connected to the conveying means to impede the flow of the developer material passing the image bearing surface to increase said development contact.

16. The apparatus of claim 15 wherein the force field means applies a magnetic force.

17. The apparatus of claim 15 including means to rotate the disc surface around an axis extending substantially perpendicular to the image bearing surface.

18. The apparatus of claim 17 wherein the force field means applies a force through the disc surface to impede the flow of developer material thereon.

19. The apparatus of claim 18 wherein the force field means applies an annular force field substantially about the center of the disc surface.

20. The apparatus of claim 19 wherein the force field means comprises a magnetic field inducing means to impede the flow of developer flow on the disc surface to increase development contact with the image bearing surface.

21. The apparatus of claim 20 wherein the disc surface comprises an annular member and including means to effect developer material flow in outward directions on the annular

member.

22. An apparatus for developing a support surface bearing a latent electrostatic image with developer material comprising surface means including a disc surface rotatably mounted about an axis substantially perpendicular to an image bearing surface and supporting developer material for development by contact with the image bearing surface, motion inducing means operatively connected to the surface means to effect movement thereof about said axis, and

force field inducing means including magnetic field generating means mounted adjacent the surface means to control the development contact between the developer material and the image bearing surface.

23. The apparatus of claim 22 wherein the magnetic field generating means creates a magnetic field about the axis.

24. The apparatus of claim 22 wherein the surface means is coupled to means to induce developer flow thereon in multiple directions past the image bearing surface to be developed.

25. The apparatus of claim 24 wherein force field means controls the developer material by impeding the flow of developer material on the surface means.

26. A method of developing latent electrostatic images comprising

radially propelling developer material from a housing journaled for rotation about an axis generally perpendicular to a support surface bearing a latent electrostatic image to be developed and directing the developer material over the latent image during its radial travel in a plane generally parallel to the support surface to obtain multiple direction contact between the developer material and support surface.
